UNITED STATES PATENT OFFICE.

JOHN STUMPF, OF CHICAGO, ILLINOIS.

HYDRAULIC MOTOR.

SPECIFICATION forming part of Letters Patent No. 643,831, dated February 20, 1900.

Application filed December 15, 1896. Serial No. 615,801. (No model.)

To all whom it may concern:

Be it known that I, JOHN STUMPF, a subject of the Emperor of Germany, residing at Chicago, in the county of Cook and State of Illinois, have invented a new and useful Improvement in Hydraulic Motors, (patented by me in Great Britain March 23, 1897, No. 7,507,) of which the following is a specification.

My invention relates to improvements in hydraulic motors or engines of the class wherein water under pressure is directed alternately against opposite ends or bearing-surfaces of a piston or plunger to reciprocate the same; and my object is to provide certain improvements in the construction and operation of the valves which control the flow of the water, whereby they will be quick and positive in their seating and unseating movements and free from all danger of sticking, all to the end of rendering the motor quickly responsive to its motive power, easy-running, and noiseless.

In carrying out my invention I provide the inlet and outlet ports of the motor chamber or chambers with valves which "lift" or open away from their seats in the direction opposite to the flow of the water. The valves are closed by means of mechanical valve-closing devices, which operate to seat the inlet-valve of a motor-chamber just before the end of the stroke of the plunger under the force of the incoming water and to seat the outlet-valve just before the end of the discharge-stroke of the plunger, whereby the further travel of the plunger in the first said instance will produce suction in the chamber to act against the outlet-valve and open the same and in the second said instance will effect increased pressure in the chamber to act against the inlet-valve and open the same.

My invention, generally stated, consists, first, in a construction of hydraulic-motor-valve-operating means, whereby either the inlet or outlet valve, or both, are closed by mechanical valve-closing means and opened by variations of pressure in the motor-chamber, and, second, in the construction of a double hydraulic motor, wherein the valves of one motor are closed by mechanical valve-closing mechanism actuated by movement of the plunger in the other motor.

In the drawings, Figure 1 is a broken view

showing in section a single hydraulic motor constructed with my improvements and geared to a pump which it is intended to operate; Figs. 1^a and 1^b, enlarged broken sections on lines 1^a and 1^b of Fig. 1; Fig. 2, a broken top plan view of the motor and pump shown in Fig. 1; Fig. 3, a broken view showing a single hydraulic motor of the differential type constructed with my improvements, the motor being in section and the pump to which it is geared being in elevation; Fig. 4, a top plan view of a double hydraulic motor geared to and operating a double pump; Fig. 5, a broken view showing the same in side elevation; Fig. 6, an enlarged broken view, partly in section, the section being taken on line 6 of Fig. 4 and viewed in the direction of the arrow; Figs. 7 and 8, enlarged sections taken on lines 7 and 8 of Fig. 4; Fig. 9, a broken view showing in section a double motor of the differential type geared to a pump, which is shown in broken side elevation; and Fig. 10, a broken diagrammatic view showing my improvements applied to a mine.

Referring to Fig. 10, T is the shaft of a mine; V, an engine, and V' a pump, both at the surface of the mine; A, a hydraulic motor, and B a water-raising pump, both located at the bottom of the mine; C, a water-pressure supply-pipe extending from the pump or supplier down the shaft T to the motor A, and B² a discharge-pipe extending from the pump B to the surface of the mine.

In each of the motors illustrated in the drawings the water which operates the machine enters an air-chamber at the lower side and passes out at the top or upper side. The inlet-ports are at the lower sides of the piston chambers or cylinders and the outlet-ports at the upper sides thereof. All the valves, both inlet and outlet, at the piston chambers or cylinders open by moving from their seats in the direction from which the water flows and are provided with valve-closing means of the same character, but varying in specific construction in accordance with requirements.

Referring to all the constructions, A is the hydraulic motor, and B the pump. Each motor is provided at its under side with an air-chamber A', communicating toward its lower side with the supply-pipe C and provided with one or more hand-holes having remov-

able covers Z. The single motors illustrated in Figs. 1, 2, and 3 have a single piston chamber or cylinder E, while the double motors illustrated in the remaining figures have two piston chambers or cylinders E and E'. Working in the cylinders are pistons F on stems F', which pass through stuffing-boxes t in the cylinder-heads and through stuffing-boxes B' at the pumps B, the stems being also the stems of the pistons of the pumps B and suitably constructed for that purpose. The differential motors are provided at their cylinders with a single inlet-port s at the lower side and a single outlet-port s' at the upper side, the opposite end of the chamber or cylinder being in open communication with the air-chamber A' through a port r. In the other motors illustrated each of the cylinders or chambers E E' is provided at its lower side with two inlet-ports s, communicating with the air-chamber A', and at its upper side with two outlet-ports s'. Each inlet-port s at its lower or outer side affords a valve-seat s², and each outlet-port s' at its lower or inner side affords a valve-seat s³. Each of the ports s s' is formed of a casting having an outer ring, secured in the opening through the cylinder-shell and a spider having a central sleeve s⁴. At each inlet-port is an inlet-valve G, opening downward or in the outward direction with relation to the cylinder or chamber E and closing upward against the seat s², and at each outlet-port s' is an inwardly-opening valve H, which closes upward against the seat s³.

Referring in detail first to the motor shown in Figs. 1 and 2, the chamber or cylinder E is provided at opposite end portions with inlet and outlet ports s s', as described, the piston F working in the cylinder between the end portions thereof. On the piston-stem F' in the positions shown are stops or heads q q', preferably in the form of disks, and in the cylinder-heads at opposite ends of the chamber E are dash-pots q² q², which the heads or disks q q' enter as the piston nears the end of its stroke. The valves G are formed with upward or inwardly projecting stems p, which pass through the guide-sleeves s⁴. On the upper end of each stem p is a cup p', held in place by a nut p². Below the cup p' and sliding upon the stem p is a cup or engaging piece p³, provided with a circumferential flange p⁴. Surrounding the stem and confined between the cups p' p³ is a stiff spring p⁵. (See Fig. 1^b.) The under side of the cup p³ is provided with a recess p⁶, which fits loosely over the top of the sleeve s⁴, whereby when the valve G opens the movement of the recess p⁶ over the end of the guide-sleeve s⁴ operates as a dash-pot to prevent shock. Each valve H has a stem n passing through it and to which it is secured. The stem above or at the outer side of the valve works through the sleeve s⁴ and is provided at its upper or outer end with a cup n', held in place by a nut n². The cup n' is adapted to fit over the upper end of the adjacent sleeve s⁴ and afford a dash-pot which neutralizes any shock upon the valve as the latter opens. Loose upon the stem n below or at the inner side of the valve H is a flanged sleeve or engaging piece n³, which is pressed against a nut n⁴ on the lower end of the stem by means of a stiff spring n⁵, confined between the sleeve and valve. At each valve H is a swinging valve-closer I in the form of a bell-crank lever, having the bifurcated finger m (see Fig. 1^a) and single downward-projecting finger m'. The valve-closer may be mounted on a rock-shaft m², pivoted at opposite ends in flanged plugs m³ in the shell of the chamber. The bifurcated finger m bears against the lower end of the flanged sleeve n³ on opposite sides of the nut n⁴, and the finger m' extends downward into the path of a stop or shoulder q³ on the piston-stem F'. In the chamber or cylinder at each valve G is a valve-closer I' in the form of a bell-crank lever, mounted upon a rock-shaft in the same way as the valve-closer I and having a single upward-projecting finger l and a bifurcated finger l', which loosely embraces the cup p³ and bears against the under side of the flange p⁴ at opposite sides of the cup. The finger l at the valve G to the right in Fig. 1 projects upward into the path of the stop q, and the finger l' at the valve G to the left in Fig. 1 projects upward into the path of the stop q'. Above or at the outer sides of the discharge-valves H are chambers K, which are shown open at the top and in communication through a pipe K'. K' is the outlet-pipe. Should the pipe K' extend to any material distance below the level of the chamber or cylinder E, the tops of the chambers K may be closed in order that the siphoning power of the outflowing water may be utilized.

Where my improved motor is to be employed in a mine, it may be located at the bottom of the mine, and the pipe C would extend up the shaft and connect with a hydraulic pump at the surface of the mine, as shown, for example, in Fig. 10. Water forced from the surface-pump downward through the pipe C enters the air-chamber A'. In order that the motor may be initially started, I provide at each valve G a priming and starting passage k, extending from the air-chamber A' to the cylinder or piston-chamber above the valve G. At each passage k is a valve k', which may be opened and closed at will. Each valve k' is provided with an operating-handle k², which, if desired, may be in the form of a pulley-wheel, (see Figs. 4, 5, and 10,) around which operating-ropes x x' may extend to the surface of the mine, so that the valves may be operated from the surface in the event that the mine is flooded. To start the motor, one valve k' is opened to allow the water under pressure to enter one end of the cylinder and force the piston F to the opposite end. That valve is then closed and the other opened, if necessary, to force the piston in the contrary direction to the end of its stroke, after

which the last-named valve is closed and the motor is in operation. Fig. 1 shows the valve G to the left open, the valve H to the right closed, the valve H to the left closed, and the valve H to the right open, and the piston F moving in the direction of the arrow. As the disk or head q nears the respective dash-pot q^2 the disk or head q' engages the finger l at the open valve G, and the stop q^3 engages the finger m' at the open valve H. In the further movement of the piston F and attendant parts the said finger l is swung to turn its companion bifurcated finger l' upward, whereby it raises the valve G to its seat at the same time as it travels beyond the closing-point, compressing the spring p^5 . The engagement of the stop q^3 with the finger m' at the open valve H causes the bifurcated finger m to engage the sleeve n^3 and lift the said valve H to its seat at the same time as it travels beyond the closing-point, compressing the spring n^5 . The said valves G H are closed just before the piston reaches the end of its stroke, whereby in its further travel it effects a suction action in the chamber to the left of the piston and a preponderance of pressure in the chamber to the right of the piston. Therefore as soon as the said valves G and H are closed, as described, pressure being raised above the other valve G causes the latter to drop and open, the shock in its opening being neutralized by the dash-pot at p^6 , as before described. At the same time the pressure being reduced at the opposite end portion of the cylinder below the other valve H causes the latter to drop and open, the shock in opening being neutralized by the dash-pot at n' . The water under pressure from the air-chamber A' then enters through the port s to the right in Fig. 1 and moves the piston F to the left in that figure, while the water in the chamber to the left of the piston is discharged past the then open valve H. Just after the piston starts to the left the respective stops q', q^3 release engagement with the respective mechanical valve-closers I I', the closed valve H remaining closed under the pressure in the cylinder and the closed valve G remaining closed under the superior pressure in the air-chamber. As the disk q' nears the respective dash-pot q^2 the stop q^3 to the left of the piston strikes the finger m' in its path to close the respective valve H, and the stop or disk q strikes the finger l in its path, closing the respective valve G. Thus the reciprocation of the piston F is continuous, and its slight further travel after the respective valves are closed causes the other valve H to be opened by suction and the other valve G to be opened by pressure in the piston-chamber. The water discharged into the chamber K flows out at the pipe K^2 . The dash-pots q^2 neutralize all shock upon the piston and attendant parts when through inertia or otherwise the piston moves to or beyond the intended limit of its stroke.

While the valves may open by gravity in the constructions shown, their opening is

quickened by the inertia of the piston, which, however slight, tends after an inlet-valve is closed to create a relative vacuum below the adjacent valve H, and after an outlet-valve is closed to effect a relatively-excessive pressure against the upper side of the adjacent inlet-valve. This construction, involving the downwardly-opening valves with mechanical valve-closing means operating in the movement of the piston, affords a particularly-positive and smooth-running motor. My principal object in providing the inlet-valves at the lower side and the outlet-valves at the upper side of the piston-chamber is to provide an upward course for the water, which will expel all air, and the parts are so constructed that no space can exist in the piston-chamber for the accumulation and storage of air, which by its expansion and contraction would render the motor more or less inoperative.

When the motor and pump shown are employed in a mine, the force which operates the motor would be the force of the pump at the surface and the weight of the water-column in the pipe C, less friction. As the weight of the water-column would give power, more or less, nearly sufficient to raise the same amount of water to the surface of the mine, the greater part of the power contributed by the pump at the surface may be utilized to pump additional water from the mine. In practice the pipe K^2 may lead to the inlet-chamber of the pump B or to the sump-hole, from which the pump B sucks water.

In the differential motor shown in Fig. 3 the stem F' of the piston F is provided at the piston with a stop q^3 and at its inner end with a disk q , adapted to work in the dash-pot q^2 in the end of the chamber or cylinder. The inlet-valve G, outlet-valve H, and mechanical valve-closers I I' are the same as in Fig. 1. The piston F is of substantially the same construction as that employed in differential pumps, and a knowledge of the working of a differential pump, in view of the above explanation in connection with Fig. 1, will render the operation of the differential motor, here shown, clear. In the movement of the piston to the left the disk or stop q strikes the finger l before the opposite end of the piston arrives at the dash-pot q^2 , adjacent to the stuffing-box t . Turning of the finger l with the bifurcated finger l' of the valve-closer I' closes the valve G and causes the valve H to open. As the pressure in the chamber E on the valve side of the piston is thus cut off the latter is moved to the right by the water-pressure against the ring area y of the differential piston until the stop q^3 strikes the finger m' and closes the valve H, whereby the valve G opens.

In the construction shown in Figs. 4, 5, 6, and 7, which show a double motor of substantially the same type as the single motor shown in Fig. 1, each of the pistons F may be longer than the piston in the single motor and is connected through its piston-rod with one of

the pistons of a double pump B. In these figures I have not shown dash-pots q^2 , though they may be provided, as in Fig. 1, if desired. As in a double motor it is desirable that the 5 mechanical valve-closers for the valves of one motor shall be geared to the other motor in order that the motors shall coöperate and work in unison, I have changed the valve-closing mechanism for double motors from 10 that shown and described in connection with the single motor to better adapt it to the requirements. Each of the inlet-valves G has a hollow outward or downward projecting stem or sleeve h , which slides upon a vertical 15 guide-rod g , fastened at its upper end in the sleeve s^4 in the inlet-port and at its lower end in a socket x^3 at the base of the air-chamber. On the sleeve h in the position shown is a 20 flange h' , and loose upon the said sleeve is an outer sleeve h^2 , having a flange h^3 . Surrounding the sleeve h^2 and confined between the flanges h' h^3 is a stiff spring h^5 , which tends 25 to press the sleeve h^2 downward against a stop-nut h^4 on the sleeve h . Each outlet-valve H has an upward or outward projecting stem f , which slides through the adjacent stationary 30 guide-sleeve s^4 and has a reduced and threaded upper end portion f' , presenting a shoulder f^2 . (See Fig. 6.) Loosely surrounding 35 the stem f is a flanged sleeve or bearing-piece f^3 , and screwed upon the upper end of the stem is a flanged sleeve f^4 , which moves through a guide-opening in a spider x^2 at the top of the motor-casing. Confined between 40 the flanged sleeves f^3 f^4 is a stiff spring f^5 , which tends to press the sleeve or bearing-piece f^3 down against the shoulder f^2 . Extending 45 through the shell of the air-chamber A' at each valve G is a rock-shaft e, journaled in a suitable stuffing-box and extending past the adjacent sleeve h . Firmly secured to each rock-shaft e is a bifurcated lever or finger e' , which straddles the adjacent nut h^4 and bears against the under surface of 50 the flange h^3 of the sleeve h^2 . Extending through the shell of each motor, above each outlet-valve H, is a rock-shaft d, suitably journaled in a stuffing-box in the shell and carrying a bifurcated lever or finger d' to engage 55 the under surface of the bearing-piece f^3 . The shafts e, d at one end of each motor are provided beyond the shell with bell-crank levers e^2 d^2 , and the other shafts e, d are provided with crank-arms e^3 d^3 . The crank d^3 60 on each side of the double motor is geared by means of a connecting-rod d^4 with one arm of the bell-crank lever d^2 on the same side, the other arm of the bell-crank lever being 65 geared by a connecting-rod d^5 to one arm of the bell-crank lever e^2 on the same side, the other arm of the bell-crank lever e^2 being geared to the crank e^3 on that side by means of a connecting-rod e^4 . Fixed upon each of 70 the piston-stems F' is a recessed collar c. 75 Mounted in standards b, b upon the motor-frame is a rock-shaft b', having at one end a

downward-projecting arm b^2 , which at its lower end enters and loosely engages one sleeve c at the recess in the latter. On the opposite end of the shaft b' is a crank-arm b^3 , 70 from which extends a connecting-rod b^4 , which at its opposite end is pivotally connected with the crank d^3 at one side of the double motor. Also mounted upon the motor-frame are standards a, a, in which is journaled a rock-shaft a', having a downward-extending arm a^2 , which loosely engages the recess in the other sleeve c, the shaft a' carrying at its other end a crank a^3 , geared at its free end through the medium of a connecting-rod a^4 80 with the crank d^3 on the side of the double motor opposite the crank d^3 before mentioned. Thus the gearing is such in each instance that the crank d^3 on one motor is actuated from the piston of the other motor. The gearing between each member of a set of valve-closing levers or fingers d' e' is such that one lever d' is raised while the other lever d' is lowered, and each valve-closing finger e' is moved at the same time in the direction contrary to the lever d' directly above it. As the piston F of one motor moves to the left in Fig. 4 the piston of the other motor moves to the right. Thus as each piston-stem moves it causes all the shafts d e of the other motor 95 to be rocked. When, for example, the shaft d to the left in Fig. 6 is rocked to the position there shown, its lever d' engages the under surface of the bearing-piece f^3 and raises it to seat the valve H, the sleeve f^4 passing upward through the guide x^2 . When the valve H is closed, any slight further movement of the lever d' will compress the spring f^5 . At the same time the lever e' to the left in Fig. 6—that is to say, at the same end of 100 the cylinder—is rocked downward to the position shown, permitting the valve G, with its sleeve h and nut h^4 , to descend until they are stopped by impact against the rod-securing socket-piece x^3 at the bottom of the air-chamber. At the same time the lever d' to the 105 right in Fig. 6, or opposite end of the cylinder, is rocked downward, permitting the valve H at that end to descend, and the lever e' at the same end is rocked upward to engage the flange h^3 and lift the sleeves h^2 h and valve G until the latter is closed, after which any further rise of the lever e' will compress the spring h^5 . This opening and closing of the valves causes the water under pressure to rise 110 through the valve G, to the left, and drive the piston in the direction of the arrow, the water in the opposite end of the cylinder escaping through the open valve H. A reversal of the movement of the piston F is brought about by the rocking of the fingers e' d' in the opposite direction from that stated, whereby the valve H to the right in Fig. 6 is closed by the lever d' and the valve G at the same end is opened, and the valve G to the left in that 115 figure is closed, and the valve H at the same end opens. Thus the piston of one motor in

its movement controls the movement of the piston in the other motor and the motors work in unison.

In the double differential pump shown in Fig. 9 the valves G H are constructed in the same way as the valves in the other double motor described, and the mechanical valve-closers, with the levers $d^2 e^2$, are the same. Each shaft d is provided beyond the casing with a bell-crank lever like the bell-crank lever d^2 described, and each shaft e is provided with a crank like the crank e^2 described. On the stem of each piston F is a recessed collar c , and substantially the same mechanism is employed as that described in the other double motor to rock the valve-closers.

In my improved motor, whether single or double and differential or not, the inlet-valves opening outward and the outlet-valves opening inward require mechanical means, as distinguished from the water-pressure in the cylinder, to close them as the piston nears the end of its stroke, and the valves are opened by variations of fluid-pressure in the chamber, and my invention is not to be limited to the specific construction of the valves or valve-closers shown. In motors of certain constructions it may not be necessary that both the inlet and outlet valves or all of them shall

move from their seats, though any such valve in a hydraulic motor opening in the direction from which the water flows and closed when the piston nears the end of its stroke by mechanical valve-closing means, substantially as and for the purpose above described, would be within the spirit of my invention. While the inlet-valves open in the outward direction and the outlet-valves in the inward direction with relation to the piston-chamber, it is not essential that they shall move in a vertical plane, though this construction is preferred, because it is believed to be more simple and avoids the necessary use of springs for opening the valves. More or less horizontally-moving valves which leave their seats may be substituted, if desired, for the vertically-moving valves shown and provided, when required, with springs to completely open them.

It is desirable that the outlet-valves shall be closed, as stated, before the piston reaches the end of its stroke, so that the inlet valve or valves may be quickly opened by the pressure produced by the piston in its final movement. In the construction shown I rely for the quick opening of the valves upon the inertia of the piston. To increase the inertia, the piston may be solid or hollow and filled, as with water, to give it weight.

Obviously my improvements, which are here shown in the form which I now believe the most simple, may be variously modified with regard to details of construction without departing from the spirit of my invention as defined by the claims.

What I claim as new, and desire to secure by Letters Patent, is—

1. In a hydraulic motor, the combination with the piston and piston-chamber having inlet and outlet ports, of an outwardly-opening valve at the inlet-port with means for closing it, a valve governing the outlet-port and mechanical valve-closing means therefor operating to close the outlet-valve during the movement of the piston toward the end of its discharge-stroke, whereby the inlet-valve is opened by the increase of pressure in the piston-chamber resulting from the further movement of the piston after the outlet-valve is closed, substantially as described. 70

2. In a hydraulic motor, the combination with the piston and piston-chamber having inlet and outlet ports, of an outwardly-opening valve at the inlet-port with means for closing it, a valve governing the outlet-port 85 with mechanical valve-closing means therefor operating to close the outlet-valve during the movement of the piston toward the end of its discharge-stroke, whereby the inlet-valve is opened by the increase of pressure in the piston-chamber resulting from the further movement of the piston after the outlet-valve is closed, and means for cushioning the inlet-valve in its opening movement, substantially as described. 90

3. In a hydraulic motor, the combination with the piston and piston-chamber having inlet and outlet ports, of an inwardly-opening valve at the outlet-port with means for closing it, a valve governing the inlet-port 100 and mechanical valve-closing means therefor operating to close the inlet-valve during the movement of the piston, whereby the outlet-valve is opened by the suction in the piston-chamber resulting from the further movement of the piston after the inlet-valve is closed, substantially as described. 105

4. In a hydraulic motor, the combination with the piston and piston-chamber having inlet and outlet ports, of an inwardly-opening valve at the outlet-port with means for closing it, a valve governing the inlet-port with mechanical valve-closing means therefor operating to close the inlet-valve during the movement of the piston, whereby the outlet-valve is opened by the suction in the piston-chamber resulting from the further movement of the piston after the inlet-valve is closed, and means for cushioning the outlet-valve in its opening movement, substantially 110 as described. 115

5. In a hydraulic motor, the combination with the piston and piston-chamber having inlet and outlet ports, of lift-valves governing said ports, opening in the direction opposite to the flow of the liquid, and mechanical valve-closing devices for the said valves operating to close them alternately in the opposite movements of the piston toward the ends of its strokes, whereby each valve is opened 125 by the change of pressure in the chamber resulting from the further travel of the piston after the other valve is closed, substantially as described. 130

6. In a hydraulic motor, the combination with the piston and piston-chamber having inlet and outlet ports, of lift-valves governing said ports, opening in the direction opposite to the flow of the liquid, mechanical valve-closing devices for the said valves operating to close them alternately in the opposite movements of the piston toward the ends of its strokes, whereby each valve is opened by the change of pressure in the chamber resulting from the further travel of the piston after the other valve is closed, and means for cushioning the valves in their opening movements, substantially as described.
15. 7. A double hydraulic motor having, in combination, two piston-chambers each provided with an inlet-port at its lower side and an outlet-port at its upper side, and an outwardly-opening valve at the inlet-port, a piston in each chamber, and mechanical valve-closing means at each said valve for closing the same, operatively connected with the piston in the other chamber to be actuated thereby, substantially as and for the purpose set forth.
25. 8. A double hydraulic motor having, in combination, two piston-chambers each provided with an inlet-port at its lower side and an outlet-port at its upper side, and an inwardly-opening valve at the outlet-port, a piston in each chamber, and mechanical valve-closing means at each said valve for closing the same, operatively connected with the piston in the other chamber to be actuated thereby, substantially as and for the purpose set forth.
35. 9. A double hydraulic motor having, in combination, two piston-chambers each provided with an inlet-port at its lower side and an outlet-port at its upper side, an outwardly-opening valve at the inlet-port, and an inwardly-opening valve at the outlet-port, a piston in each said chamber, and mechanical valve-closing means for each said valve operatively connected with the piston in the other chamber and actuated thereby to close the inlet and outlet valves in each said chamber alternately, substantially as and for the purpose set forth.
45. 10. In combination, a water-pressure supplier, and a double hydraulic motor having two piston-chambers each provided toward one end with an inlet-port, at the lower side, and an outlet-port, at the upper side, each said inlet-port and each chamber, toward its opposite end, communicating with said supplier, a differential piston in each chamber, valves at said ports, and mechanical valve-
50. closers, at each said valve, operatively connected with the piston in the other chamber to be actuated thereby to close the valves in each chamber alternately, substantially as and for the purpose set forth.
55. 11. In a hydraulic motor, the combination, with the piston and the piston-chamber having an inlet-port at its lower side and an outlet-port at its upper side, of an outwardly-opening valve at the inlet-port having a stem, a bearing-piece on the stem and a spring confined between the said piece and a stop on the stem, and a piston-actuated valve-closer having a finger engaging the said piece, whereby in the movement of the piston toward the limit of its traverse in one direction, the said valve-closer, through the medium of the said piece and spring presses the valve yieldingly to its seat, substantially as and for the purpose set forth.
60. 12. In a hydraulic motor, the combination, with the piston and the piston-chamber having an inlet-port at its lower side and an outlet-port at its upper side, of an inwardly-opening valve at the outlet-port having a stem, a bearing-piece on the stem and a spring confined between the said piece and a stop on the stem, and a piston-actuated valve-closer having a finger engaging the said piece, whereby in the movement of the piston toward the limit of its traverse in one direction, the said valve-closer, through the medium of the said piece and spring, presses the valve yieldingly to its seat, substantially as and for the purpose set forth.
65. 13. In a hydraulic motor, the combination, with the piston, and piston-stem, and the piston-chamber having an inlet-port at its lower side and an outlet-port at its upper side, of an outwardly-opening valve at the inlet-port, an inwardly-opening valve at the outlet-port, each valve being provided with a yielding bearing-piece, a stop movable with the piston, a head on the piston-stem, a dash-pot in the piston-chamber, into which the said head moves, and a valve-closer at each valve having a finger engaging the yielding bearing-piece on the valve, and a finger projecting toward the piston-stem, one into the path of the said moving stop, and the other into the path of the head, all constructed and arranged to operate substantially as and for the purpose described.

JOHN STUMPF.
